RUPERT E. RUNDELL, OF ROCKVILLE CENTER, NEW YORK, ASSIGNOR TO INTERNATIONAL CIGAR MACHINERY COMPANY, A CORPORATION OF NEW JERSEY.

CIGAR-BUNCH MOISTENER FOR CIGAR MACHINES.

Application filed December 3, 1923. Serial No. 678,349.

To all whom it may concern:

Be it known that I, RUPERT E. RUNDELL, a citizen of the United States, residing at Rockville Center, county of Nassau, and State of New York, have invented a new and useful Improvement in Cigar-Bunch Moisteners for Cigar Machines, of which the following is a specification.

This invention relates to a cigar bunch moistener for cigar machines.

In making fresh bunch cigars by machinery, a charge of filler is enclosed in a binder to form a bunch; the bunch so formed is then manipulated to evenly distribute the filler within the binder; and the ends of the manipulated bunch are then subjected to the action of bunch shapers which compress the bunch ends to give them their permanent form, after which a wrapper is applied to the bunch. The shaper used has coacting jaws which engage the bunch and when the machine is running, the sticky juices exuding from the tobacco in the bunch accumulate upon the operating surfaces of the shaping elements; consequently the shaping elements must be cleaned from time to time, and this entails stoppage of the machine and a decrease in its production.

It has been found that this difficulty can be overcome by moistening the ends of the bunch before they are subjected to the action of the shaping devices, and the main object of the present invention is the production of a device for so moistening them. With this and other objects not specifically mentioned in view, the invention consists in certain combinations and constructions which will be hereinafter fully described and then specifically pointed out in the claims hereunto appended.

In the accompanying drawings, which form a part of this specification and in which like characters of reference indicate the same or like parts, Fig. 1 is a front elevation, partly in section, of moistening means constructed in accordance with the invention; and Figs. 2 and 3 are detailed views of the moisture applying devices shown in Fig. 1.

In carrying the invention into effect, there is provided a support for a cigar bunch, dampening means normally spaced from said bunch, and means for producing a relatively approaching movement of said support and said dampening means to cause the

latter to act on a bunch on said support. These parts may be widely varied in construction within the scope of the claims, for the particular device selected to illustrate the invention is but one of many possible concrete embodiments of the same. The invention therefore is not to be restricted to the precise details of the structure shown and described.

Referring to the drawings, 4 is a support for a cigar bunch of a type well known in the art and operating to transfer a cigar bunch from a manipulating device to a locating device wherein it is positioned endwise, and thence to a shaping device where its ends are compressed.

Rising from the upper surface 5 of the cigar machine bed in connection with which the present device is used, are two standards 6 spaced apart. Each of the standards 6 has an outwardly extending integral bracket 7, and fast on a short shaft 8 journaled in a suitable bearing in the outer end of one of the brackets 7 is a lever 9—10. Also fast on the shaft 8 is an arm 11 pivotally connected at 12 with a connecting rod 13, the latter being reciprocated by one of the cams of the cigar machine and operative connections.

To the lower end of the arm 11 of the lever 9—10 is pivoted one end of a link 14. The opposite end of this link is pivoted to an arm 15 fast on a short shaft 16 journaled in a suitable bearing in the outer end of the bracket 7 before referred to, to the left in Fig. 1. By means of the structure just described, reciprocation of the connecting rod 13 will cause the upper ends of the lever 9—10 and of the arm 15 to approach or to retreat from each other. The arm 9 of the lever 9—10 and the arm 15 carries at its upper end a roller 17. Each roller 17 engages a groove 18 in a collar 19 pinned on a shaft 20 which is movable in a bearing 21 formed in the upper end of each standard 6. Pinned to adjacent ends of the shafts 20 are locating heads or thimbles 22. When a cigar bunch is brought by the support 4 into position between the heads 22, it may not be properly located for further action by the shaping mechanism. The approaching movement of the two locating heads 22 is then produced; and since the heads travel to definite positions (indicated by

the dotted lines in Fig. 1), a bunch, if not properly located on the support, will be first engaged by one of the heads and pushed to its proper position wherein it touches both heads. The mechanism so far described is old and well known in the art.

For the purpose of moistening the bunch ends to prevent the tobacco juices from sticking to the shaper elements in the next 10 operation, the bunch locating means is provided with one or more dampeners. With this end in view, each of the locating heads 22, instead of being solid metal as heretofore, are hollowed out and a felt plug 23 is 15 inserted therein, said plug having a concavity 24 similar in form to that of the old locating heads. Behind this felt plug is formed a chamber 25 adapted to contain a small quantity of water whereby the felt 20 plug 23 is kept moist.

For the purpose of imparting a rotary motion to the heads 22 during their approaching and retreating movements, each of the shafts 20 is provided with a spiral 25 groove 26, and this groove is engaged by a stud 27 threaded into the boss 21 before referred to. By an inspection of Figs. 2 and 3, it will be noted that the width of the groove 26 is greater than the diameter of the stud 27. The purpose of this is as follows: When the approaching movement of the heads 22 occurs, they are rotated in the direction in which the binder is wound about the cigar, so that just as the two heads 30 properly locate the cigar bunch, a slight wiping action of the felt plug 23 on the extreme ends of the bunch occurs. To avoid disturbing the binder at the ends of the bunch during the first part of the retreating movement of the heads 22, the groove 26 is made wide enough to permit the heads to move back without turning far enough to clear the bunch ends, after which they are rotated 35 in a reverse direction by the engagement of the studs 27 with the grooves 26.

The supply of water in the chamber 25 is very small and means are provided for augmenting this supply. With this end in view, a bracket 28 is mounted in the top of each 50 of the bearings 21, and this bracket supports a reservoir 29 containing water and having a gravity valve 30, the lower end of which engages a groove 31 from each head when the heads are in the position shown in 55 Fig. 1 and adjacent thereto. A small aperture 32 is drilled from the bottom of the groove 31 into the chamber 25, so that water may flow from the groove 31 into the said chamber to augment the supply therein.

The valve 30 is so close a fit in its bearing that water will not run down along the valve stem when the same is at rest. Nevertheless, there is a sufficient clearance between the valve stem and its bearing to permit delivery of water from the reservoir 29,

drop by drop, by capillary action when the valve is agitated. This agitation occurs once in each machine cycle of operations. By an inspection of Fig. 1, it will be noted that the upper end of the valve 30 is larger 70 than the lower end. When the approaching movement of the heads 22 occurs, the lower end of the valve stem rides off of the same and the valve drops until the upper enlarged end of the valve completely cuts off the flow 75 of water from the reservoir even by capillary action. Upon the return stroke, or the retreating movement of the heads 22, the lower end of each valve comes into engagement with the conical part of the head 22 and is kicked upward thereby. This action shakes down a drop of water which finds its way through the aperture 32 into the chamber 25. Thus, the dampening felt plug 23 is kept moist, and accumulation of sticky 80 juices on the shaper elements is prevented without machine stoppage and without decrease of machine production.

What is claimed is:

1. A cigar bunch moistener comprising a support, a dampener, and means for producing a relative approaching movement of said support and said dampener to cause said dampener to act on a bunch on said support. 90

2. A cigar bunch moistener comprising a support, a dampener, and means for moving said dampener towards said support to cause said dampener to act on a bunch on said support. 95

3. A cigar bunch moistener comprising a support, a dampener, and means for producing a relative approaching movement of said support and said dampener to cause said dampener to act on a bunch on said support, said dampener including an applying member of felt and means for keeping said felt moist. 100

4. A cigar bunch moistener comprising a support, a dampener, and means for producing a relative approaching movement of said support and said dampener to cause said dampener to act on a bunch on said support, said dampener including a rocking thimble closed by a felt disc having a concave operating surface, and means for keeping said felt moist. 110

5. A cigar bunch moistener comprising a support, a dampener, and means for producing a relative approaching movement of said support and said dampener to cause said dampener to act on a bunch on said support, said dampener including a rocking thimble forming a liquid reservoir and closed 115 by a felt disc having a concave operating surface. 120

6. A cigar bunch moistener comprising a support, a dampener, and means for producing a relative approaching movement of said support and said dampener to cause said 125 support, a dampener, and means for producing a relative approaching movement of said support and said dampener to cause said dampener to act on a bunch on said support, said dampener including a rocking thimble forming a liquid reservoir and closed by a felt disc having a concave operating surface. 130

dampener to act on a bunch on said support, and an inverted and intermittently-operated valve-controlled liquid fountain for supplying liquid to said dampener.

5 7. A cigar bunch moistener comprising a support, a dampener, and means for producing a relative approaching movement of said support and said dampener to cause said dampener to act on a bunch on said sup-

port, said dampener including a rocking 10
thimble forming a liquid reservoir and closed
by a felt disc having a concave operating
surface, and an inverted valve-controlled
liquid fountain intermittently operative to
replenish the liquid in said reservoir. 15

In testimony whereof, I have signed my
name to this specification.

RUPERT E. RUNDELL.
